UNITED STATES PATENT OFFICE.

EMILE JOSEPH FEUILLETTE, OF PARIS, FRANCE.

HACKLING OR BRAKING MACHINE.

1,036,820.

Specification of Letters Patent. Patented Aug. 27, 1912.

Application filed June 20, 1908. Serial No. 439,580.

To all whom it may concern:

Be it known that I, EMILE JOSEPH FEUILLETTE, a citizen of the Republic of France, and a resident of Paris, Seine, France, have 5 invented certain new and useful Improvements in Hackling or Braking Machines, of which the following is a full, clear, and exact description, such as will enable others skilled in the art to which it appertains to 10 carry out the same.

This invention relates to an improvement in hackling machines for flax or similar fibers and the principal advantages of the machine are certainty of operation with 15 high production and a perfection of effect with a small expense of power. Furthermore, the device is not affected in its operation by irregularities in separating of the fiber, by passage of extraneous bodies, etc. 20 The machines made according to this invention treat such tangled fibers as "Argentine flax" equally well with other fibers.

The invention is illustrated in a preferred form in the accompanying drawings, 25 wherein—

Figure 1 is a vertical section through the machine, Fig. 2 is an end elevation of the machine, Fig. 3 is a plan view of the same, Fig. 4 is a vertical section, showing the use 30 of two machines one over the other, Figs. 5, 6 and 7 illustrate respectively on a larger scale a vertical section, a plan and an end view of a single stamp. Fig. 8 is a sectional view of a stamp, Fig. 9 is a similar view of 35 the same on the line $a-a'$ in Fig. 8, Figs. 10 and 11 are side and face views of a nut forming part of the spring adjustment for each stamp, Fig. 12 is a side view of the outer bearing for the supplemental spring 40 for avoiding jar, Fig. 13 is a face view of the same, Fig. 14 is a side view of the internal spurred adjusting nut for the main stamp spring, Fig. 15 is a face view of the same, Fig. 16 is a side view of the abutment 45 for the main stamp spring, Fig. 17 is a face view of the same.

The material after suitable preliminary treatment, well known to those skilled in the art, is delivered to the hackling machine 50 through the duct 34 where it is caught between the upper fluted cylinders 35 and 36. These cylinders like those which follow directly afterward and are similar thereto need be only sufficiently rough to serve the 55 purpose of the feeding function which they

perform; they are preferably shown fluted as this is a form of roller which is suitable to a greater variety of fibers. The cylinders numbered 37 to 44 inclusive, preferably fluted as shown, are located below and serve 60 to feed the material as it descends vertically.

Between the pairs of feeding cylinders are located stamps and dies opposed to each other, the dies being shown in the form illustrated at 45 all fixed upon a single vibratory 65 frame 46, whereby they may be moved back and forth as hereinafter described. These dies extend along the width of the machine as shown in Fig. 2. Opposite the dies are located the stamps shown at 47, these being 70 plural for each single die and in the particular form, eight of these stamps being provided for each single wide die 45. Thus each die corresponds horizontally to eight stamps 47. The stamps are supported by a 75 frame 48 which also receives a horizontal motion and each stamp has at its extremity a toothed formation corresponding and feeding into a similar system of teeth on the dies 45. By bringing all the stamps and 80 dies together rapidly by vibratory movement of the framework of each, as herein-after described, the hackling operation takes place upon the passing fibers which are struck between the teeth of the stamps and 85 dies. It is obvious that suitable variations in speed may be made and suitable variations in the relation of the vibratory speed to the feeding speed to suit the machine to various purposes and various materials. 90 The frame 46 carrying the dies is supported upon pivoted levers 150 while similar pivoted levers 151 carry the frame 48 upon which the stamps are mounted. Vertical levers are fixed upon the rocker shafts 156, 95 one end of each lever being connected by pivoted rods 153 to the frame 46 while the opposite end of each lever is connected similarly to the frame 48. The shafts 156 are rocked by means of bars 157 pivotally connected by the rod 161 to each other, and by the pitman 158 to the crank 159 of the driving wheel 160. Thus the revolution of this wheel causes the stamps and dies to move back and forth for the purposes hereinafter 100 described.

As shown in Fig. 1, I prefer to provide vacuum ducts or pipes 49 and 50, whereby the boon is carried away through secondary ducts terminating between the bars of feed- 110

ing cylinders. The material issuing from the last cylinders 43 and 44 falls upon the suitable transferring device for instance as shown in the drawings. It comprises two sets of wooden blades 51, 52 crossing each other and alternating. These blades are hinged at 53 and 54 and have for their function to shake the material and free it from a further quantity of boon. These blades beat against the endless apron 55 close to which lies another endless apron 56, the material is cut at 57, between these two inclined aprons, and is finally delivered at 58, where it falls upon an inclined board 59 by which it is led to the feeding cylinders 60 and 61 of a second hackling machine. This latter comprises also the feeding cylinders 62 to 69 inclusive as well as dies and stamps 70 and 71 mounted upon frames 72 and 73, all in the same manner as heretofore described. Main vacuum ducts 74 and 75 are provided and branch or secondary ducts connect therewith in the manner already described with respect to the first half of the machine. The material leaving the lower cylinders 68 and 69 is again shaken by blades 76 and 77 whence it may be delivered to other hackling machines similar to those described. It is preferred to make the teeth on the dies and stamps finer and finer in proportion as the work advances.

Fig. 4 shows another arrangement in which the hackling machines are superposed and the endless apron 80 is arranged over the blades 81 and 82 similar to 51 and 52 and pivoted at 83 and 84. The material issuing from the lower cylinders 85 and 86 of the upper hackling machine is thus delivered to the upper cylinders 87 and 88 of the following machine. A sheet iron blade 89 causes the evacuation of the boon.

I prefer to make the stamps as shown in the drawings at 47 or at 71 made for instance of cast steel and built up preferably as shown in Figs. 5, 6 and 7. They are located near each other between cross beams 90 (Figs. 1 and 7) parallel to each other and secured to the movable frame 48. Abutting on the other face of each stamp is a central rod 91, having a square bearing at 92 and a threaded portion at 93. This rod has its bearing on the stamp at 94, in a recessed boss 95. A ring 96 is screwed upon the threaded portion 93 of the rod and bears a spur 97 which slides in the axial groove 98 of the stamp. This ring is shown in detail in Figs. 14 and 15 and the spur 97 prevents rotation under the action of the central screw. The coil spring 99 rests upon the ring 96, and a hollow ring 100 shown in detail in Figs. 16 and 17 receives the pressure of this spring at its opposite end. The ring 100 is provided with lugs 101 whereby it is fastened across the cross beams 90. It will thus be seen that the ring 100 and,

therefore, the left end of the spring 99 in Figs. 5 and 6 maintains a fixed position with respect to the cross beams 90 and the frame 48. The small coiled spring 102 is located in the chamber 103 of the hollow ring 100 and is held fast by a ring 104 screwing into the head 105 on the stamp. This latter ring is shown at Figs. 10 and 11 and is for instance four lugs 106 any one of which may be made to come opposite the lug 107 which is carried by the head 105 of the stamp. The ring 104 is provided with a chamber 108 in which is located a polygonal nut 109 shown in detail in Figs. 10 and 11. A pin 110 in the square rod 92 prevents loosening of the nut.

Fig. 8 shows a sectional plan view of the stamp 47 and Fig. 9 a sectional elevation made on the line *a—a'*. The stamp is provided with teeth at its extremity shown at 111 and the die has opposed teeth 112 so formed as to have a certain play in the corresponding cavities on the stamp.

The operation of the various parts of each stamp is as follows. The ring 105 abuts upon the ring 100 but may be separated therefrom when the stamp 47 is subjected to a pressure superior to the resistance of the spring 99. When by any accident this superior pressure is experienced between the stamp and the die, the sleeve of the stamp 47 slides within the cylinder 90. The ring 105 with the parts fixed thereto, shown at 104, 106 and 109, etc., moves away from the ring 100 which serves as an abutment to the spring 99 and when the extra pressure is removed from between the stamps and dies, the spring 102 prevents the return of the ring 105 from being too sudden and serves as a cushion.

From the foregoing it will be understood that the material passing between the feeding cylinders, either continuously or intermittently, receives the repeated action of the stamps and dies as they move back and forth. When any foreign matter or extra thickness of fiber is carried between the teeth 111 and 112, the stamp 47 yields by compression of the spring 99. Thus no damage occurs and the one stamp alone affected is momentarily thrust backward.

What I claim is—

1. In a hackling machine and in combination, guiding rollers, a broad die near the path of movement of the material near said rollers, a plurality of separately movable stamps set in a row opposite said die and adapted to act in opposition thereto, separate resilient means for holding each stamp up to its work and means for causing relative movement of said stamps and dies in a direction across the path of movement of the material, substantially as described.

2. In a hackling machine and in combination, pairs of guiding rollers and opposed

dies and stamps placed alternately in the path of movement of the material, said stamps and dies being provided with teeth, resilient means for holding each stamp up to its work and means for causing relative movement of said stamps and dies across the path of movement of the material; the teeth on said stamps and dies being progressively smaller in the direction of ad-

vance of the work, substantially as de- 10 scribed.

In testimony whereof I have hereunto set my hand in the presence of the two subscribing witnesses.

EMILE JOSEPH FEUILLETTE.
